CLAIM

The ornamental design for a tire cover, as shown and described.

DESCRIPTION

FIG. 1 is a front perspective view of a tire cover, showing my new design;

FIG. 2 is a rear perspective view thereof;

FIG. 3 is a front elevational view thereof;

FIG. 4 is a rear elevational view thereof;

FIG. 5 is an enlarged top plan view thereof;

FIG. 6 is an enlarged bottom plan view thereof; and,

FIG. 7 is an enlarged right side view thereof, the left side being a mirror image thereof.
